UNITED STATES PATENT OFFICE.

ARTHUR GUTBERLET, OF LEIPZIG-GOHLIS, GERMANY.

MACHINE FOR FEEDING SHEETS OF PAPER.

SPECIFICATION forming part of Letters Patent No. 761,069, dated May 31, 1904.

Application filed September 22, 1902. Serial No. 124,449. (No model.)

To all whom it may concern:

Be it known that I, ARTHUR GUTBERLET, a subject of the Emperor of Germany, whose post - office address is Aeussere Hallesche- 5 strasse 135, Leipzig-Gohlis, Germany, have invented certain new and useful Improvements in Machines for Feeding Sheets of Paper; and I do hereby declare the following to be a full, clear, and exact description of the invention, 10 such as will enable others skilled in the art to which it appertains to make and use the same.

This invention relates to a pneumatic taking-off device for paper-feeding machines in which sheets of paper are fed from a pile, and 15 has for its object to provide a taking-off device which shall insure the removal of only one sheet at a time.

In the drawings, Figure 1 is a longitudinal section of a feeding-machine fitted with the 20 taking-off device; Fig. 2, a section along the line N N, Fig. 1; Fig. 3, an elevation showing the front edges of the unfolded sheets after the sheet has been transmitted by the suckers *a* to the suckers *b*; Fig. 4, a side view 25 of the same.

The essential feature of the invention is the lifting of the top sheet of the pile of paper by means of two suckers *a b*, the one sucker *a* oscillating around a fixed point and lying on 30 the pile of paper and bending the top sheet against the other sucker, *b*, which is fixed and retains the sheet of paper bent and then released by the first sucker until the conveying-rollers *d g* are forced to convey the same to 35 the laying-on board *h*. The suckers *a b* are held by a fixed bar *s*, placed transversely over the machine-table *k*, the suckers *a* being pivoted at *i* in such a way that they can be swung downward so far that their under surfaces 40 come into the same horizontal plane as the holding-rail *s*, Fig. 1, in dotted lines and Fig. 4. The fixed suckers *b* are held by the bar *s* and arranged at an angle in relation to the pile of paper, Fig. 4. The swinging motion 45 of the suckers *a* is imparted by the lever *n*

through the medium of the link *m*. The lever *n* is firmly keyed to the shaft *p*, which is moved backward and forward from a suitable spot in the machine driving-gear at regular intervals for the purpose of lowering and rais- 50 ing the suckers *a*.

The shafts *r o*, supporting the conveying-rollers *d g*, are held by swinging arms *u v*, which are moved toward one another by suitable cam-disks mounted on a cam-shaft *w* and 55 operating the arms *u v* through rocking arms *x y* and rods *u' v'*. The rollers *d g* are thus brought together and pressed against opposite sides of the raised sheet, the roller *g* being at the same time rotated to feed the sheet for- 60 ward by a suitable driving-pulley *z* and belt- ing *z' z''*.

The suckers *a b* are each connected with a separate suction-pipe *e f*, which either, as in the form illustrated, lead to one or to separate 65 suction apparatus. In both cases care must be taken that the pipe *f* can be wholly or partially shut off for a time, which can be effected by means of a valve *t*, opened and closed me- chanically by the machine. The suction-pipe 70 *e* may be arranged to work continuously or intermittently. The only condition is that it shall act as soon as the suckers *a* have raised the top sheet of paper, so that the suckers *b* retain the sheet of paper until the conveying- 75 rollers *g d* take hold of it and, continuing to rotate, carry it to the laying-on board. In consequence of the sudden complete or par- tial interruption of the suctional action of the suckers *a*, the raised sheet of paper held by *b* 80 is so forcibly shaken that should the follow- ing sheet of paper be adhering to it it must be loosened and falls onto the pile of paper before the conveying-rollers *d g* are moved in the direction of the sheet. 85

What I claim, and desire to secure by Letters Patent, is—

In machines for feeding sheets of paper from a pile, a pneumatic taking-off device comprising fixed suckers mounted at an angle to the 90

plane of the paper, movable suckers adapted to bend the front part of the top sheet upward and lay it against the surfaces of the inclined and fixed suckers, means for wholly or partially putting the movable suckers out of action in order to release the sheet of paper now held by the fixed suckers and also to shake the sheet to cause the following sheet of paper

should it have been bent with the top sheet to fall onto the pile of paper.

In testimony whereof I have affixed my signature in presence of two witnesses.

ARTHUR GUTBERLET.
